CLAIM

The ornamental design for a power adapter, as shown and described.

DESCRIPTION

FIG. 1 is a front and top perspective view thereof.

FIG. 2 is a front and bottom perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The black broken lines bounding the half-tone de-emphasized shaded areas illustrate portions of the power adapter that form no part of the claimed design.
